(57) **CLAIM**

The ornamental design for household energy storage inverter, as shown and described.

DESCRIPTION

The patent or application file contains at least one drawing executed in color. Copies of this patent or patent application publication with color drawing(s) will be provided by the Office upon request and payment of the necessary fee.

1. Household energy storage inverter

1.1 : Reference view 1

1.2 : Reference view 2

1.3 : Front

1.4 : Back

1.5 : Left

1.6 : Right

1.7 : Top

1.8 : Bottom 1. The name of this design product: household energy storage inverter. 2. Use of this design product: used in energy storage system to realize bidirectional conversion of alternating current and direct current. 3. Design points of this design product: in shape and structure. 4. The picture or photograph that best illustrates the point of the design: reference 1.

The broken lines illustrate portions of the household energy storage inverter that form no part of the claimed design.
